UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

WARP STOP MOTION FOR LOOMS.

Application filed July 20, 1922. Serial No. 576,292.

To all whom it may concern:

Be it known that I, JONAS NORTHRUP, a citizen of the United States, residing at Hopedale, in the county of Worcester 5 and State of Massachusetts, have invented certain new and useful Improvements in Warp Stop Motions for Looms: and I do hereby declare the following to be a full, clear, and exact description of the invention, such as will enable others skilled in the art to which it appertains to make and use the same.

The present invention relates to an improvement in warp stop motions for looms.

Upon the breaking of a warp, a drop wire falls and stops the loom. Now to find where the break occurred is sometimes a matter of difficulty because the upper end of the drop wire is concealed in the body of 20 the wires and the lower end of the drop wire is not easily visible. The object of the present invention is to produce a warp stop motion which will not only stop the loom upon the dropping of the wire, but will 25 open the warp at the broken warp ready for piecing. To this end, the present invention consists in the warp stop motion hereinafter described and particularly defined in the claims.

In the accompanying drawings illustrating the preferred form of the invention; Figure 1 is a sectional elevation of the loom with the invention embodied therein; Fig. 2 is a plan of the same, the arch being 35 shown in section; Fig. 3 is an enlarged plan of a portion of the mechanism; Figs. 4 and 5 illustrate portions of the mechanism in different positions; Figs. 6 and 7 illustrate the operation of the device on the dropping 40 of a wire to open the warp; Fig. 8 is a perspective view of the actuating device for the stop motion; and Fig. 9 is a detail of construction hereinafter referred to.

The illustrated embodiment of the invention is described as follows: The warp extends from the warp beam 1 over the whip roll 2 to the drop wires 3, through the lease rods 4, heddles 5, through the lay 6, and thence to the sand roll 7 and take up roll 8. 50 The weft hammer 9 is actuated by the cam 10 in the usual manner. The drop wires 3 are supported in a frame 11 in the usual manner, except as hereinafter described. The warps pass one through a drop wire in 55 one bank and the other through a drop wire

in the second bank passing over the warp supporting rods 12 in the usual manner. The frame 11 is provided at its bottom with a ladder 13 so that when a warp breaks and a drop wire falls, as shown in dotted lines 60 in Figs. 6 and 7, it falls between the wires 14 of the ladder 13. The detector bar 15 is serrated, as shown, and engages the drop wire and pushes it laterally to one side, as shown in Fig. 6. A separator 16 is provided 65 in the center of the bank of drop wires which consists of a plate provided with grooves 17 to receive and guide the detectors 15. The separator 16 is provided with a pin 17' which passes through a hole 18 70 in the frame 11 and it is normally held in vertical position by the spring 19 which draws it up to and holds it against the frame 11. When a drop wire falls, the first movement of the detector bar to the 75 left, as seen in Fig. 2, engages the fallen wire and pushes that wire and others beyond it along into the position shown in Fig. 6, thereby opening the warp and forming a clear indication of the place where 80 the drop wire fell, enabling the operative quickly to find and piece the broken warp. An additional separator 16, exactly similar to that above described, is provided at 85 the side of the loom toward which the drop wires are caused to be pushed on failure of a warp, as shown in Fig. 2.

The detector bars 15 are supported in the grooves 17 in the separator 16 and are normally reciprocated by means of their 90 connection to the detector lever 20. The lever 20 is provided with a striker 21 which is pivoted to the lever at 22 and normally occupies the position shown in Fig. 4, being held there by the compression springs 23 received in the socket in the end of the detector lever 20. Downwardly extending arms 24 attached to the striker carry a pin 25 to which the detector bars 15 are attached. It will be seen that as the detector lever 95 moves to the left pushing the detector bars with it, it meets the resistance presented by a dropped wire pressing against other wires and warps and causes a thrust to be exerted upon the detector bar, which tips the striker 21 about its pin 25, thereby raising it to the position, as shown in Fig. 5, so that upon the reverse movement of the detector lever 20, the striker will be in position 105 to engage a member, presently to be de- 110

scribed, by which the loom is knocked off. To the detector lever 20 is attached the arm 26 by means of which the detector lever is oscillated. To the end of the arm 26 is attached a block 27 by means of a pin 28. This block 27 receives the operating rod 29 which passes through a vertical hole in it and is secured thereto by nuts 30, one above and the other below the block. The operating rod 29 is provided on its lower end with a block 31 which normally rests on the arm 32 attached to the rear end of the weft hammer lever 9, as shown in Fig. 8. As the weft hammer lever rises and falls, it lifts the detector operating rod 29 and allows it again to descend. If the rod 29 is held in raised position by the means described as occurs when breakage is detected, the weft hammer may descend without pulling down the rod 29, see Fig. 1. A coiled spring 33 normally tends to swing the detector lever 20 to the right, as shown in Figs. 4 and 5, thereby retracting the detector bar and constituting means for pulling the bar to the right, as viewed in Figs. 4 and 5. Upon the detection of warp breakage and the occurrence of resistance to the free movement of the detector bar to the left, as shown in Fig. 4, the striker is elevated, as has been described, so that its outward end wipes against the under side of a striker plate 40, whereupon at the beginning of the return movement of the detector bar, the end of the striker having risen engages the striker plate and pushes it to the right, as viewed in Fig. 4, so that it occupies the position illustrated in Fig. 5. This striker plate 40 has a base 41 which is adjustably attached to the rock lever 42 pivoted at 43 on the bracket 44 secured to the arch, as shown in Fig. 2. The lever 42 is secured to the rock shaft 45 and its forward end 46 passes under the knock-off slide rod 47 connected at its forward end to the knock-off lever 48 and supported at its rear end in the slot 49 in the plate 50 forming a part of the bracket 44. The knock-off slide rod 47 carries a striker 51 which is adapted to be struck by the striker plate 52 carried by the lay, see Fig. 9, so that when the knock-off slide rod is elevated in the manner described, upon the next backward movement of the lay the striker plate 52 will engage the striker 51 and exert a pull upon the rod which will cause the knock-off lever to release the shipper lever 53 and thereby stop the loom. The rock lever 42 is provided with a pin 60 which is received in the slot 61 in the plate 50 so that the movement of the lever 42 is limited.

60 A stop 70 is secured to the loom frame and provides a support for the arm 26 which operates the detector lever 20 so that when the detector lever is moving toward the right, it can move only so far as the stop 70 permits. The arm 26 attached to the detector

lever 20 is provided with three holes 71 in either one of which the pin 28 may be placed to adjust the stroke of the detector bar.

It will be observed that the resistance offered by the warp to the lateral movements of the drop wires when one of them falls and engages the detector slide, operates through the means described to knock off the loom. The detector slide normally reciprocates freely through the drop wires except when one of them falls and engages it and then its motion is less in extent than otherwise it would be causing it to tip the striker into operative position.

Having thus described the invention, what is claimed is:

1. A warp stop motion for looms having, in combination, a set of drop wires, a detector slide provided with teeth, means for actuating the detector slide, a shipper lever, and connections between the detector slide and the shipper lever, the warps operating on the falling of a drop wire to oppose a resistance to the reciprocation of the slide and thereby cause loom stoppage. 90

2. A warp stop motion for looms having, in combination, a set of drop wires, means for supporting the drop wires provided with devices to hold the lower end of a fallen drop wire from lateral motion, a detector slide having teeth adapted to engage a fallen drop wire and to push the drop wires beyond it to inclined position whereby opening the warp. 95

3. A warp stop motion for looms having, in combination, a set of drop wires, means for supporting them provided with a ladder below the lower ends of the drop wires between the rungs of which a fallen wire will extend, a detector slide provided with teeth 105 to engage the upper part of a fallen wire and tip it, and with other drop wires beyond to inclined position to open the warp and to indicate position of a breakage.

4. A warp stop motion for looms having, in combination, a set of drop wires, means for supporting them provided with devices supported below the drop wires to engage the lower end of a drop wire when it falls and to hold it from lateral motion, a detector slide adapted to engage the upper end of a fallen drop wire and to push it and the wires beyond laterally so as thereby to tip them into inclined position and indicate the position of the broken warp, and a spring supported separator for normally maintaining the drop wires in position. 110 115 120

5. A warp stop motion for looms having, in combination, a set of drop wires, a detector slide, means for reciprocating the detector slide to engage a fallen drop wire, a striker connected with the slide adapted to be lifted when the detector slide engages a fallen drop wire so as thereby to be moved to an operative position, a rock lever hay- 125 130

ing a portion adapted to be engaged by the striker in its operative position, a knock-off slide rod provided with a striker, a lay, a striker plate carried by the lay adapted to hit the slide rod striker when the latter is moved by the rock-lever, a snipper lever, connections between the knock-off slide rod and the snipper lever having provision for operating the latter to knock off the loom after the knock-off slide rod is lifted upon the first rearward movement of the lay.

6. A warp stop motion for looms having, in combination, a set of drop wires, means for supporting them, means for moving the wires laterally, and a separator arranged to yield when the drop wires are moved.

7. A warp stop motion for looms having, in combination, a set of drop wires, means

for supporting them, means for moving the wires laterally to open the warp when one of the wires falls, and means to cause loom stoppage through the resistance of the warps to lateral movement of the wires.

8. A warp stop motion for looms having, in combination, a set of drop wires, a detector having a plurality of teeth, a continuously oscillating lever, connections between the oscillating lever and the detector for reciprocating the latter including a striker normally movable with the lever but adapted for movement relative to the lever when the motion of the detector is opposed, and means cooperating with the striker when the latter is moved relatively to the lever for initiating knock-off of the loom.

JONAS NORTHROP.
